(57) **CLAIM**

The ornamental design for a connector box for light cable as shown and described.

DESCRIPTION

FIG. 1 is a bottom, front and right side perspective view of a connector box for light cable showing our new design; FIG. 2 is a top, rear and left side perspective view thereof; FIG. 3 is a front elevational view thereof; FIG. 4 is a rear elevational view thereof; FIG. 5 is a left side view thereof; FIG. 6 is a right side view thereof; FIG. 7 is a top plan view thereof; FIG. 8 is a bottom plan view thereof; and,

FIG. 9 is a bottom, rear and right side perspective view showing the connector box for light cable in a disassembled and open state.

The broken lines in the drawings illustrate portions of the connector box for light cable which form no part of the claimed design.

1 Claim, 9 Drawing Sheets
